2 SHEETS—SHEET 2.

UNITED STATES PATENT OFFICE.

HENRY HIGGIN AND CLIFFORD TRAUT, OF NEWPORT, KENTUCKY, ASSIGNEES TO THE HIGGIN MANUFACTURING COMPANY, OF NEWPORT, KENTUCKY, A CORPORATION OF WEST VIRGINIA.

SCREEN FOR REVOLVING WINDOWS.

1,165,671.

Specification of Letters Patent.

Patented Dec. 28, 1915.

Application filed April 27, 1915. Serial No. 24,328.

To all whom it may concern:

Be it known that we, HENRY HIGGIN and CLIFFORD TRAUT, citizens of the United States, and residents of the city of Newport, 5 in the county of Campbell and State of Kentucky, have invented certain new and useful Improvements in Screens for Revolving Windows, of which the following is a full, clear, and exact description, reference being 10 had to the accompanying drawings, forming part of this specification.

Our invention relates to screens for revolving windows, wherein the window is pivoted at or near its median line and the 15 screens are mounted one on one side and the other on the other side of the window. In screens of this type it is necessary to provide means on the window or the screen to maintain a contact between the two during the 20 revolving or opening of the window.

Our invention is directed to means for providing screens having simple mountings in the window frame, and for providing adjustable contact devices between the window 25 sash and the screen members, whereby a close fit may be maintained.

It is also an object of our invention to provide for certain play in the screen members, whereby the closeness of the fit of said 30 contact means will not cause a binding of parts upon the opening of the window.

These objects we accomplish by that certain construction and arrangement of parts to be hereinafter more specifically pointed 35 out and claimed, wherein the upper screen member is located on the outside of the window and the lower screen on the inside thereof, and play is allowed for so that the upper screen may have a slight upward movement 40 and the lower screen may have a slight outward movement.

In the drawings, Figure 1 is a front elevation of the window taken from the inside. Fig. 2 is a vertical section of the middle of 45 the window taken on the line 2, 2, of Fig. 1. Fig. 3 is a horizontal section taken on the line 3, 3, of Fig. 6, with the outside of the window toward the observer. Fig. 4 is a horizontal section taken through one of the 50 muntins of the sash, showing the small closing plate and turned toward the observer as in Fig. 3. Fig. 5 is a rear elevation of the window, from the outside. Fig. 6 is a side elevation of the window frame and window. Fig. 7 is a perspective view of the

frame member for the upper screen. Fig. 8 is a perspective view of a portion of the outside contact plate. Fig. 9 is a like view of the inside contact plate.

The window is shown as being mounted on the frame members 1, 2, 3 and 4 of a steel sash construction (Figs. 1 and 5). The window has a sash having side members 5 and 6 and top and bottom members 7 and 8 respectively. A pivot pin 9, inserted through the frame and the sides of the sash at each side, serves as a hinge on which the sash revolves, and the sash has flanges 10 located on the outside below and on the inside above. The window frame has like flanges 11, which are located on the inside below and the outside above, whereby the window when revolved will only swing into positions with the upper portion inwardly and the lower portion outwardly extending (Fig. 3). This sash and frame form no part of our invention, but are merely a structure now on the market and selected by us for purposes of illustration. The window sash has the usual muntins 13, 13, for holding the glass 14, 14, and is adapted to revolve on the hinges or pivots now briefly referred to so as to swing the sash portion below the center of the window outwardly and the portion above the center inwardly.

Suitably secured (by rivets or the like) to the frame members of the window are screen holders formed of angle iron. The upper screen holder has side bars 15, 15, and a top bar 16, and it is set onto the window frame with the inwardly projecting flange 17 of the angle iron against the frame (Fig. 7) and the open side of the holder extending out from the window. Clips 18, 18, are mounted on the top bar 16 to hold the upper end of the upper screen, and slots 19, 19, are formed in the lower ends of the side bars to hold the lower end of the screen, as will be described.

The upper screen has top and bottom frame members 20, 21, and side members 22, 22, and mounted at the sides of the said frame at the two bottom corners are spring-pressed pins 23 having handles 24. When the screen is to be placed into its holder the top portion is slipped up under the clips 18, 18, from the outside and the pins 23 pulled in and then allowed to spring out into the slots 19, 19. The parts are so proportioned that when the pins 23 lie in the bottom of

the slots 19, the top of the screen will not abut against the holding frame, and therefore the screen is so mounted that it may be pushed upwardly a short distance, owing to 5 the sliding of the pins in their respective slots.

The lower screen has a holder likewise made of angle iron, and having side bars 25, 25, and a bottom bar 26. The inwardly extending flange 27 of this holder likewise abuts against and is secured to the window frame, and the clips 28, 28, are mounted on the bottom bar. The lower screen has top and bottom frame members 29 and 30, and 10 side members 31, 31. Mounted on the window frame at each side are small brackets 32, 32, which have mounted on them the pivoted fingers 33, 33. These fingers are positioned so as to be swung over the screen 15 when mounted in its holder, and the screen has mounted on each side frame member 31, 31, a spring strip 34, 34, against which the said fingers will abut. In mounting the lower screen, therefore, it is placed into its 20 holder from the front with its lower frame member behind the clips 28, and the fingers 33 are swung over into contact with the spring strips 34. The screen will then be capable of a slight outward movement to 25 accommodate the window sash contact plates, as will be hereinafter developed.

A spring catch 35, mounted on the upper member of the window sash, serves to hold shut the window, and this catch is released 30 and the top of the window pulled down inwardly by means of a chain 36 depending from the catch and held by a slotted plate 37.

The upper frame member 29 of the lower screen and the lower frame member 21 of the upper screen lie adjacent to the median line or axis of the revolving window sash, and contact plates are provided as heretofore mentioned to maintain the space between these members and the window sash 45 closed in all positions of the window.

The lower contact plate having side members 38, 38, and a rounded end 39 (Fig. 9) has mounting plates 40 at each side which are secured by screws 41 to the sash. It is 50 also closed at each end by plates 42, and is cut away at 44, to clear the muntins of the sash.

There are provided together with the contact plate a set of extension clip plates 45 55 formed of a beaded fold of metal, which are adapted to clamp over the inner edges of the contact plate, one strip to extend between each muntin clearance cut 44. The plate is therefore mounted fixedly on the window 60 sash and the extension strips are adjustable when set in place to close off all spaces between the edges of the contact plate and the window exactly. When the window swings on its pivots the rounded side of the plate 65 will maintain a constant contact with the

upper frame member of the lower screen, and any resultant binding will be allowed for by the freedom of the lower screen to move outwardly in its mounting as already detailed.

70

The outside contact plate is similar in construction to the inside plate. It has the side members 46, 46, and a rounded face 47. This outside contact plate is held against the sash by means of plates 49, having 75 screws 50 by which they are adjustably secured in the slots 51 formed in the upper and lower side of the contact member. The plates 49 close the ends of the contact member, and have flanges 52 which extend outwardly and are inserted underneath the mullion 53 of the window sash, the putty being scraped away for this purpose. This contact member is likewise provided with extension clip plates 45 as in the case of the 80 inner contact member. The clamp plates 54 are provided for adjustably mounting this outside or upper contact member. These plates are fastened to the muntins of the sash in the following manner (Fig. 4). The 85 plates are cut away to closely fit over the muntin and a portion 55 of the metal is turned up in making said cut so as to extend up along the muntin. The plates are secured to the upper side of the contact member, by means of tongues 56, 56, formed by cutting away a portion of the plates and turning it downwardly, said tongues extending through slots (not shown) formed in the contact member. A triangular clip 57 90 is provided adapted to hook under the muntin at 58 and having a set screw 59 to bear against the portion 55 of the plates. This method of mounting the upper contact member does not form a part of this invention, but is adopted herein as providing a 95 convenient method of adjustably securing the said contact member to the window sash.

It is believed that the various details of our invention have now been described and 100 their advantages and method of operation noted. It is not desired, because of detailed description unaccompanied by reference to possible mechanical changes, to exclude from the application of the claims that follow, 115 equivalent structures, where the wording of said claims permits.

Having thus described our invention, what we claim as new and desire to secure by Letters Patent, is:—

120

1. In a device of the character described, in combination with a revolving window, and a frame therefor, an upper and a lower screen holder mounted on the frame; one outside and one inside of the window, means 125 for resiliently and detachably retaining the screens in said holders, and curved contact plates on the window to bear on the screens, said plates having side portions extending toward the window and adjustable exten- 130

sion strips on the side portions to completely close the space between the side portions and the window.

2. In a device of the character described, 5 in combination with a revolving window, and a frame therefor, a screen holder mounted on the frame, means for resiliently and detachably retaining the screen in said holder, and a curved contact plate on the 10 window to bear on the screen, said plate having side portions extending toward the window and adjustable extension strips on the side portions to completely close the 15 space between the side portions and the window.

3. In a device of the character described, in combination with a revolving window having its axis near its median line, a frame for said window, upper and lower screen 20 holders on the frame, and means in said holders for holding the one screen resilient to move upwardly and the other resilient to move outwardly, and curved contact members on the window and positioned to contact with the screens.

4. In a device of the character described, in combination with a revolving window, and a frame therefor, a screen for said window, means for mounting the screen in the 30 frame, with its upper end adjacent to the axis of the window, a contact plate mounted on the window, said plate having side portions extending toward the window, and extension strips on said side portions to abut 35 tightly against the window, said contact means positioned so as to ride against the upper end of the screen.

5. In a device of the character described, in combination with a revolving window, 40 and a frame therefor, a screen, a holder for the screen mounted on the frame, said holder being open away from the window so that the screen may be easily set and removed, means to hold the screen at the 45 base of the holder, spring strips at the base of the screen, and holding members mounted on the frame and engaging over the spring strips, resiliently holding the upper end of the screen in the holder, and curved contact

means on the window centered substantially 50 along its axial line and positioned so as to ride against the top of the screen.

6. In a device of the character described, in combination with a revolving window, and a frame therefor, a screen, a holder for 55 the screen, mounted on the frame, said holder being open away from the window so that the screen may be easily set and removed, means to hold the screen at the top of the holder, slots in the holder at the 60 lower sides, and members mounted on the screen and adapted to project into the slots, said projecting members being adapted to slide in the slots, and said screen being of a size that it does not abut the top of the 65 holder when in normal position therein.

7. In a device of the character described, in combination with a revolving window, and a frame therefor, a screen, a holder for the screen mounted on the frame, said 70 holder being open away from the window so that the screen may be easily set in and removed, means to hold the screen at the top of the holder, slots in the holder at the lower sides, and members mounted on the screen 75 and adapted to project into the slots, and projecting members being adapted to slide in the slots, and said screen being of a size that it does not abut the top of the holder when in normal position therein, means on 80 the window to contact with the lower end of the screen, and means for mounting said contact means at any desired position of the window.

8. In a device of the character described, 85 in combination with a revolving window having a sash, a screen therefor, means for mounting the screen so that its end lies adjacent to the axial line of the window, a contact plate on the window having a rounded 90 contact surface and side portions extending toward the window, end plates adjustably mounted in the contact plates so as to close the ends thereof, and projecting flanges from said end plates, adapted to be inserted 95 under the window sash mullions.

HENRY HIGGIN.
CLIFFORD TRAUT.
